SPECTACLE HOLDER

Oscar L. Newlin, Wichita, Kans.

Application March 6, 1953, Serial No. 23,932

Term of patent 7 years

(Cl. D17—12)

To all whom it may concern:

Be it known that I, Oscar L. Newlin, a citizen of the United States, residing at Wichita, State of Kansas, have invented a new, original, and ornamental Design for a Spectacle Holder, of which the following is a specification, reference being had to the accompanying drawing, forming a part hereof.

Fig. 1 is a perspective view of a spectacle holder showing my new design; and

Fig. 2 is a side view of the same holder on a reduced scale.

The broken lines in the drawing are for illustrating purposes only.

I claim:

The ornamental design for a spectacle holder, as shown and described.

OSCAR L. NEWLIN.
